US0D1090607S

(12) **United States Design Patent** (10) Patent No.: **US D1,090,607 S**
(45) Date of Patent: **** Aug. 26, 2025**

(54) **DISPLAY SCREEN OR PORTION THEREOF
WITH ANIMATED GRAPHICAL USER
INTERFACE**

(71) Applicant: **Botrista, Inc.**, Dover, DE (US)

(72) Inventors: **Kaylene Kau**, Taipei (TW); **Ching Yao Weng**, Taipei (TW); **Wu-Chou Kuo**, San Francisco, CA (US); **Alexander Milton Friedman**, San Francisco, CA (US)

(73) Assignee: **BOTRISTA TECHNOLOGY, INC.**, Dover, DE (US)

(**) Term: **15 Years**

(21) Appl. No.: **29/990,481**

(22) Filed: **Feb. 21, 2025**

CLAIM

The ornamental design for a display screen or portion thereof with animated graphical user interface, as shown and described.

DESCRIPTION

FIG. 1 is a front view of a first image of a display screen or portion thereof with animated graphical user interface showing the new design;

FIG. 2 is a second image thereof;

FIG. 3 is a third image thereof; and,

FIG. 4 is a fourth image thereof.

The outmost dot-dashed lines in the figures show a display screen or portion thereof and form no part of the claimed design. The remaining broken lines form no part of the claimed design.

The outmost dot-dashed lines in the figures show a display screen or portion thereof, and form no part of the claimed design.

1 Claim, 4 Drawing Sheets
